poration of New Jersey

Application May 1, 1934, Serial No. 723,326
In Great Britain August 30, 1933

28 Claims. (Cl. 12—9)

This invention relates to machines for use in the manufacture of shoes for shaping uppers over lasts, and is herein illustrated as applied to a machine for pulling over the uppers of stitchdown shoes, the machine shown being one of the same general type as disclosed in Letters Patent No. 1,813,983, granted on July 14, 1931, upon an application of Arthur Bates. It is to be understood, however, that in various aspects the invention is not limited to machines of the illustrated type nor to machines for operating on shoes of that particular character.

A machine organized as disclosed in the above-mentioned Letters Patent is provided with a pair of side grippers for pulling the upper transversely over the forepart of the last and with a toe gripper for subjecting the upper to longitudinal tension. An object of the present invention, among others, is to provide improved upper-pulling means such as to afford increased insurance that the upper will be satisfactorily tensioned longitudinally under all conditions; and to this end the machine herein shown has novel means whereby the toe gripper is operated to pull the upper independently of the side grippers. As illustrated, the pulling movement of the toe gripper required to stretch and shape the upper properly is effected by a spring to the action of which the toe gripper is released, the side grippers being operated by other means to which movement is imparted through a clutch. The construction shown is further such that the toe gripper is released to the action of its spring by a member which through further movement serves to actuate the clutch and thereby to start in operation the means that operates the side grippers. Accordingly, the upper is first pulled tightly about the heel end of the last and is subjected to the desired longitudinal tension by the toe gripper, after which the side grippers stretch it widthwise and pull it tightly over the forepart of the last. In accordance with a further feature of the invention, the machine herein shown is provided additionally with means for varying the path of movement of the toe gripper so that in its movement heightwise of the last it may have a component of movement either forwardly or rearwardly lengthwise of the last to adapt it better for operation on different kinds of work, as more particularly hereinafter explained.

The above and other features of the invention, including means whereby the toe gripper may be further controlled by the operator and various novel details of construction and combinations of parts, will now be more particularly described by

reference to the accompanying drawings and pointed out in the claims.

In the drawings,

Fig. 1 is a view in right-hand side elevation of a machine in which the invention is embodied, the side grippers and certain other portions of the structure being broken away;

Fig. 2 is a view on a larger scale showing the side grippers and other parts associated therewith in rear elevation and illustrating how the grippers pull an upper over a last, parts being shown in section; and

Figs. 3 and 4 are diagrammatic views illustrating different paths of movement of the toe gripper under different conditions of adjustment.

In general similarity to the disclosure of the above-mentioned Letters Patent, the machine herein shown has a head casting 10 mounted on a column 12, the casting 10 being substantially U-shaped and having vertically upstanding portions 14 on which is mounted a cross-bar 16. Supported on the cross-bar 16 is a sleeve 18 having ears 20 (Fig. 2) projecting from its opposite sides, and pivotally mounted at 21 on these ears are members 22 having upper and lower portions bored to serve as guides for a pair of side grippers arranged to grip and pull the upper at the opposite sides of the forepart. The last over which the upper is pulled is supported bottom downward, as more particularly hereinafter described, on a work support member 24 which, unlike the construction shown in the previously mentioned Letters Patent, is mounted in a fixed position on the head casting 10 and is stationary throughout the operation of the machine. The side grippers, as shown in Fig. 2, have inner jaws 26 mounted rigidly on the upper ends of hollow shank members 28 which are arranged to slide downwardly and upwardly in the guide portions of the members 22, and have also outer jaws 30 pivoted to the jaws 26 and connected by links 32 to stems 34, slidably mounted in the hollow shank members 28 for imparting upper-gripping and releasing movements to the jaws 30. Springs 35 connected at their lower ends to the shank members 28 and at their upper ends of the guide members 22 hold the grippers initially in their uppermost positions. The side grippers may be adjusted in directions lengthwise of the shoe along the cross-bar 16 by a hand screw 36 (Fig. 1) and may also be adjusted toward or from each other by a hand screw 38 (Fig. 2) in the same manner as in the prior machine. The side grippers are operated to grip and pull the upper through links 40 which connect the lower ends of the stems 34 to a sub-

stantially horizontal lever 42 mounted midway between its opposite ends on a bar 44. This bar is fast on the head 46 of a cylindrical stem 48 which is guided for vertical movements in a bore 5 in the head casting 10 and is operated as herein-after described. It will be understood that when the head 46 is carried downwardly the gripper jaws 30 are first closed upon the upper by downward movements of the stems 34, after which both 10 pairs of jaws are moved downwardly with the shank members 28 against the resistance of the springs 35 to pull the upper. In these movements of the side grippers they may turn in their guides 22, such turning movements, being limited by engagement of studs 49 in the guides with flat faces (not shown) on the shank members 28. The lever 42 is mounted to turn in a vertical plane on the bar 44 to enable the operator to move the side grippers relatively to each other while they are 15 holding the upper under tension, as in the prior machine.

The toe gripper of the machine herein shown also comprises an inner jaw 26 and an outer jaw 30 pivoted to the inner jaw and controlled by 20 links 32, the links in this instance being connected to a central stem 50 which is connected at its lower end to a spring-operated lever 52 whereby the jaw 30 is operated to grip the upper and the gripper is moved downwardly to pull the upper, as more particularly hereinafter described. The jaw 26 is fast on a shank member 54 which is controlled by a swinging link 56 pivotally connected at one end to the shank member and adjustable at its other end along an arcuate slot 58 25 formed in a bracket 60 fast on the cross-bar 16. Springs 62, one only of which is shown, are connected to the shank member 54 and yield to permit this member to be carried downwardly with the jaws to pull the upper by the operation of the lever 52 after the gripping of the upper by the initial downward movement of the stem 50 relatively to the shank member. It will be understood that when the gripper is operated to pull the upper the path of movement of its jaws is determined 30 by the swinging link 56, and by adjustment of the outer end of this link along the slot 58 the path of the jaws may be varied, as illustrated diagrammatically in Figs. 3 and 4. If the outer end of the link is set at the upper end of the slot 58, so that the link initially is substantially horizontal, as illustrated in Figs. 1 and 3, the gripper jaws will move, in pulling the upper, from the point *x* to the point *y* along a path indicated by the broken line in Fig. 3, so that the jaws as they 35 move downwardly have a component of movement lengthwise of the last in a forward direction with respect to the last, or toward the rear of the machine. This is the setting preferably used, for example, when the uppers are comparatively flexible or stretchy and are so cut that they are not unduly short or "scant." If, on the other hand, the outer end of the link is set at the lower end of the slot 58, the jaws will move from the point *x* to the point *z* (Fig. 4) with a component of movement lengthwise of the last in the opposite direction, i. e., toward the front of the machine. This often produces better results in the shaping of the toe ends of the uppers when they are comparatively stiff and, it may be, also are cut somewhat scant.

The lever 52 which operates the toe gripper is fast on a rod 64 which is mounted to turn in a bearing in the bracket 60. The lever is operated by a spring 66 connected at its lower end to the lever and at its upper end to a hook 68 slid-

ingly mounted in a lug 70 on the bracket 60. Threaded on the shank of the hook 68 is a wing nut 72 which bears on the lug 70 and may be turned to vary the tension of the spring 66. The lever 52, as illustrated in Fig. 1, is held initially against the pull of the spring 66 in a position in which the toe gripper is raised and its jaws are open to receive the upper. For this purpose there is provided a bell-crank lever 74 pivoted at 76 on an arm of the head casting 10 and controlled as hereinafter described, this bell-crank lever having on an upwardly extending arm thereof a plate 78 arranged to engage a shoulder 80 formed on a latch 82 which is pivoted at 84 on the lever 52. By engagement of the plate 78 with the shoulder 80 the lever 52 is accordingly held in its initial position. For releasing the lever 52 and thereby rendering the spring 66 effective to close and operate the toe gripper, there is provided means for lifting the latch 82 to disconnect it from the plate 78. This means comprises a pawl 86 pivotally suspended at its upper end on an arm 88 which is mounted to turn on the rod 64, the pawl engaging, in a notch therein, the lower face of a lug 90 on the latch 82. It will be understood that the latch is lifted to release the lever 52 by upward movement of the arm 88 and the pawl 86. Such upward movement of the arm and the pawl is effected by depression of a treadle 92 which is pivoted at 94 on the base of the column 12 and is connected at its rear end by a rod 96 to the arm 88. A spring 98 connected to the treadle 92 returns it to its initial position when it is released by the operator.

For operating the bell-crank lever 74 to return the lever 52 to its initial position and thereby to raise the toe gripper and open its jaws, and for also operating the side grippers to pull the upper, the machine is provided with power-driven means. This means comprises a power shaft 100 which may be driven, for example, from a belt pulley 102, and a clutch 104 arranged to be actuated to connect the shaft 100 to a gear wheel 106. The construction of the clutch is not shown in detail, since any suitable one-revolution clutch, such as one of the Horton type, may be utilized. The gear wheel 106 is in mesh with another gear wheel 108 fast on a shaft 110, this gear wheel having twice as many teeth as the gear wheel 106 so that the shaft 110 is turned through half a revolution by each revolution of the gear wheel 106. Fast on the shaft 110 is an eccentric 112 having thereon a strap 114 which is pivotally connected at its upper end to a floating lever 116 substantially midway between the opposite ends of the lever. The lever 116 is connected at its front end by a link 118 to the lower end of the stem 48 through which the side grippers are operated, and at its rear end the lever is pivotally connected to the rear end of a link 120 the front 125 end of which is pivoted at 122 on the column 12. At its rear end the floating lever 116 is further controlled by a spring 124 which surrounds a rod 126 projecting downwardly from a member 128 pivotally suspended on the rear end of the lever, the spring bearing at its upper end on the member 128 and at its lower end on a member 130 supported on the rear end of a lever 132 which is pivoted on the column 12. The member 130, through which the rod 126 extends, is threaded 130 in a collar 133 which is pivotally mounted on the forked end of the lever 132. The lever 132 is arranged to be held adjustably in a fixed position by a pawl member 134 pivotally mounted on the lever and having thereon a plurality of teeth 135

136 one or another of which is arranged to be engaged by a pin 138 on the column 12. It will thus be evident that by adjustment of the lever 132 the initial compression of the spring 124 may be varied. When the floating lever 116 is moved downwardly by the turning of the eccentric 112, downward movement is imparted thereby to the stem 48 through which the side grippers are operated to grip and to pull the upper in the manner hereinbefore described. When the resistance of the upper to the pull of the grippers becomes great enough, the rear end of the floating lever 116 is carried downwardly against the resistance of the spring 124 so that the upper is subjected to a yielding pull the force of which may be varied by adjustment of the compression of the spring as above described. It will be understood that by turning the member 130 against which the lower end of the spring 124 abuts a finer adjustment of the compression of the spring may be effected than is provided for by the teeth 136 and the pin 138.

The bell-crank lever 74 which controls the toe gripper lever 52 is itself controlled by the floating lever 116 through a link 140 connected at its upper end to a downwardly and rearwardly extending arm of the bell-crank lever and at its lower end to the floating lever 116 substantially midway between the opposite ends of this lever and immediately above the connection of the lever to the eccentric strap 114. When the floating lever 116 is moved downwardly to operate the side grippers in the manner above described, it accordingly acts through the link 140 to swing the upwardly extending arm of the bell-crank lever 74 to the right (Fig. 1) and thus to carry the plate 78 beyond the shoulder 80 on the latch 82. When the lever 116 is thereafter moved upwardly to return the side grippers to their starting positions, the upwardly extending arm of the bell-crank lever 74 is swung to the left and acts through the latch 82 to swing the lever 52 against the resistance of the spring 66 and thus to return the toe gripper to its starting position and to open the gripper jaws.

The clutch 104 is actuated to stop the gear wheel 106 at the end of each complete revolution of the latter, and accordingly at the end of each half revolution of the gear wheel 108, by a three-armed lever 142 one arm of which is arranged to engage a shoulder on a clutch ring 144. The clutch is actuated to start the power operation of the machine by swinging the lever 142 in a clockwise direction so as to release the clutch ring 144, and for this purpose there is provided an upwardly extending rod 146 having thereon a plate 148 arranged to engage a plate 150 on one arm of the lever 142. At its lower end the rod 146 is connected to the rear arm of a lever 152 mounted on the same pivot 94 as the treadle 92. The lever 152 is held in an initial position determined by a stop screw 154 by means of a spring-pressed plunger 156, and this lever is operated by the treadle 92 to trip the clutch after the toe gripper lever 52 has been released to the action of its spring 66. For this purpose a projection 158 on the treadle 92 extends into a slot 160 in the forward end of the lever 152, this slot permitting sufficient depression of the treadle to release the toe gripper lever 52 before the treadle becomes effective to trip the clutch through its movement of the lever 152. To insure the return of the lever 142 into position to stop the power operation of the machine at the end of a single revolution of the gear wheel 106 regardless of

how the operator controls the treadle 92, the machine is provided with automatic means for releasing the lever from the rod 146. This means comprises a pair of pins 162 on the end of the shaft 110, each arranged to engage a block 164 on a slide bar 166 and thus to move the bar in a forward direction. In this movement the bar 166 acts to swing the rod 146 forwardly far enough to disconnect the plate 148 from the plate 150 and thus to release the lever 142. The rod 146 is thereafter swung rearwardly again by a spring 168 which is connected to the upper end of the rod and is also connected to one arm of the three-armed lever 142 to control the latter. It will be understood that by this spring the plate 148 is again carried under the plate 150 when the operator releases the treadle.

The machine is further provided with means which may be utilized to control the toe gripper manually. This means comprises a hand lever 170 positioned at the left-hand side of the machine within convenient reach of the operator and fast on the rod 64 to which the toe gripper lever 52 is secured as hereinbefore described. By lifting this hand lever the operator may relax the force of the pull of the toe gripper on the upper, or may return the gripper to its starting position where it is again held by the bell-crank lever 74 in case, for example, it did not grip and pull the upper properly when first released to the action of the spring 66. By depressing the lever 170, on the other hand, the operator may increase the force of the pull of the toe gripper on the upper either before or after the upper has been pulled by the side grippers.

The previously mentioned work support member 24 has mounted thereon a forepart rest member 172 which is vertically adjustable by a nut 174 threaded on a stem depending from the member 172, and also a heel rest member 176 adjustable along a forward extension 178 of the member 24 and held in adjusted position by a screw 180.

In the operation of the machine, a last on which an upper is assembled is placed bottom downward on the members 172 and 176 and the margin of the upper is inserted between the open toe and side gripper jaws. The operator then depresses the treadle 92 far enough to lift the latch 82 and thus to release the toe gripper lever 52 from the bell-crank lever 74, whereupon the spring 66 swings the lever 52 to close the toe gripper jaws on the upper and to operate the gripper to pull the upper tightly about the heel end of the last and to subject it to longitudinal tension while its side margins are free of the side grippers. Before further depressing the treadle 92 the operator may, if desired, observe the condition of the upper and by manipulation of the hand lever 170 may either increase or diminish the force of the pull of the toe gripper or may return the latter to its starting position in case it did not properly grip and pull the upper. In the latter case the operator will rearrange the margin of the upper in the toe gripper and then again release the lever 52 to the action of the spring 66 by a second partial depression of the treadle. After the upper has been pulled properly by the toe gripper, the operator further depresses the treadle to trip the clutch and start the power operation of the machine, whereupon the side grippers alone are operated to grip and pull the upper, thus tensioning the upper laterally and conforming its further to the contour of the forepart of the last. Whether the opera-

tor has or has not released the treadle 92, the machine comes automatically to a stop with the side grippers holding the upper under tension. At this point in the cycle the operator may either increase or relax the force of the pull of the toe gripper on the upper by manipulation of the hand lever 170 and may adjust the upper laterally by use of the lever 42 which controls the side grippers. While the machine is thus at rest the operator secures the upper temporarily in its conformed condition by driving tacks where desired or by the use of any suitable clamping means, and thereafter again depresses the treadle 92 to trip the clutch. It will be understood that in this second depression of the treadle the pawl 86 is lifted without effect upon the toe gripper, the bell-crank lever 74 having merely been swung into position to connect again with the latch 82 in the first half of the cycle of the machine. In this second half of the cycle the toe and side grippers are returned automatically to their starting positions and release the upper, the bell-crank lever 74 returning the toe gripper lever 52 against the resistance of the spring 66.

Having described the invention, what we claim as new and desire to secure by Letters Patent of the United States is:

1. In a machine for shaping uppers over lasts, a toe gripper, side grippers, means for pulling an upper first through the toe gripper alone to subject it to substantially the full longitudinal tension required to shape it over a last, and automatic means for thereafter pulling the upper through the side grippers alone while it is held under tension by the toe gripper.
2. In a machine for shaping uppers over lasts, a toe gripper, side grippers, means for pulling an upper first through the toe gripper alone to subject it to substantially the full longitudinal tension required to shape it over a last, and power-driven means including a clutch arranged to be actuated to pull the upper thereafter through the side grippers alone.
3. In a machine for shaping uppers over lasts, a toe gripper, side grippers, means for pulling an upper first through the toe gripper alone to subject it to substantially the full longitudinal tension required to shape it over a last before it is gripped by the side grippers, and automatic means for thereafter operating the side grippers alone to grip and to pull the upper while it is held under tension by the toe gripper.
4. In a machine for shaping uppers over lasts, a toe gripper, side grippers, means for pulling an upper first through the toe gripper alone to tension it longitudinally of a last, and cyclic power-driven means for thereafter operating the side grippers alone to pull the upper while it is held under tension by the toe gripper.
5. In a machine for shaping uppers over lasts, a toe gripper and side grippers movable to pull an upper over a last at the end of the toe and the sides of the forepart respectively, cyclic power-driven means for operating the side grippers to pull the upper, and mechanism for operating the toe gripper to pull the upper independently of said cyclic means.
6. In a machine for shaping uppers over lasts, a toe gripper and side grippers movable to pull an upper over a last at the end of the toe and the sides of the forepart respectively, cyclic means including a clutch for operating the side grippers to pull the upper, and means for imparting

to the toe gripper its entire upper-pulling movement independently of said clutch.

7. In a machine for shaping uppers over lasts, a toe gripper and side grippers movable to pull an upper over a last at the end of the toe and the sides of the forepart respectively, cyclic means including a clutch for operating the side grippers alone to pull the upper, and a spring for operating the toe gripper to pull the upper.

8. In a machine for shaping uppers over lasts, a toe gripper and side grippers movable to pull an upper over a last at the end of the toe and the sides of the forepart respectively, cyclic means including a clutch for operating the side grippers alone to pull the upper, a spring for operating the toe gripper to pull the upper, and means for holding the toe gripper initially in starting position against the resistance of said spring and for releasing it to the action of the spring.

9. In a machine for shaping uppers over lasts, a toe gripper, side grippers, a spring arranged to operate said toe gripper to pull an upper over a last and of sufficient strength to subject the upper to substantially the full longitudinal tension required for the upper-shaping operation, means for releasing the toe gripper to the action of said spring to cause it to pull the upper and means for thereafter operating the side grippers to pull the upper.

10. In a machine for shaping uppers over lasts, a toe gripper, side grippers, a spring arranged to operate said toe gripper to pull an upper over a last and of sufficient strength to subject the upper to substantially the full longitudinal tension required for the upper-shaping operation, means for releasing the toe gripper to the action of said spring to cause it to pull the upper, and power-driven means constructed and arranged to operate the side grippers alone to pull the upper and to come automatically to a stop with the upper held under tension.

11. In a machine for shaping uppers over lasts, a toe gripper, side grippers, a spring for operating said toe gripper to pull an upper over a last, means for releasing said spring to render it operative on the toe gripper, and power-driven means including a clutch arranged to be actuated thereafter to cause the side grippers alone to pull the upper.

12. In a machine for shaping uppers over lasts, a toe gripper, side grippers, a spring arranged to operate said toe gripper to pull an upper over a last and of sufficient strength to subject the upper to substantially the full longitudinal tension required for the upper-shaping operation, means for maintaining said spring under an initial stress and for releasing it to render it operative to impart the upper-pulling movement to the toe gripper, and additional means for operating the side grippers to pull the upper.

13. In a machine for shaping uppers over lasts, a toe gripper, side grippers, a spring for operating said toe gripper to pull an upper over a last, means for releasing the toe gripper to the action of said spring to cause it to pull the upper, and power-driven means for operating the side grippers alone to pull the upper and for returning them to their starting positions and for also returning the toe gripper automatically to its starting position against the resistance of said spring.

14. In a machine for shaping uppers over lasts, a toe gripper, side grippers, a spring for operating said toe gripper to pull an upper over a last, means for releasing the toe gripper to the action of said

5

75

spring to cause it to pull the upper, power-driven means comprising a lever for operating the side grippers to pull the upper and for returning them to their starting positions, and mechanism for returning the toe gripper to its starting position against the resistance of said spring by movement of said lever.

15. In a machine for shaping uppers over lasts, a toe gripper, side grippers, a spring for operating said toe gripper to pull an upper over a last, power-driven means for operating the side grippers to pull the upper and for returning them to their starting positions, a device connected to said power-driven means for maintaining the toe gripper initially in its starting position and for returning it to that position against the resistance of said spring after operating on the upper, and means for disconnecting the toe gripper from said device to cause the spring to impart to said gripper its upper-pulling movement.

20. 16. In a machine for shaping uppers over lasts, a toe gripper, side grippers, a lever movable to operate said toe gripper to pull an upper over a last, a spring for imparting to said lever its operative movement, power-driven means for operating the side grippers to pull the upper and for returning them to their starting positions, a device operated by said power-driven means for returning the toe gripper to its starting position against the resistance of said spring and for maintaining it in that position, and a latch on said toe gripper lever arranged to be engaged by said device to control the toe gripper, said latch being movable to release the toe gripper to the action of its spring.

25. 17. In a machine for shaping uppers over lasts, a toe gripper, side grippers, a lever movable to operate said toe gripper to pull an upper over a last, a spring for imparting to said lever its operative movement, power-driven means for operating the side grippers to pull the upper and for returning them to their starting positions, a swinging arm connected to said last-named lever, and a latch on the toe gripper lever arranged to be engaged by said swinging arm to return the toe gripper to its starting position against the resistance of its spring, said latch being movable to release the toe gripper to the action of its spring.

30. 18. In a machine for shaping uppers over lasts, a toe gripper, side grippers, a spring for operating said toe gripper to pull an upper over a last, power-driven means for operating the side grippers to pull the upper, and a member movable by the operator to render said spring effective to operate the toe gripper and further movable to start said power-driven means in operation.

35. 19. In a machine for shaping uppers over lasts, a toe gripper, side grippers, a spring for operating said toe gripper to pull an upper over a last, a latch for holding the toe gripper initially in its starting position against the resistance of said spring, power-driven means including a clutch for operating the side grippers to pull the upper, and a member movable to operate said latch to release the toe gripper to the action of its spring and further movable to actuate said clutch and thereby start said power-driven means in operation.

40. 20. In a machine for shaping uppers over lasts, a toe gripper, side grippers, means for moving said toe gripper heightwise of a last independently of the side grippers to pull an upper over the last, and means for imparting to said toe gripper in its movement heightwise of the

last an adjustably variable movement lengthwise of the last.

45. 21. In a machine for shaping uppers over lasts, a toe gripper, side grippers, means for moving said toe gripper heightwise of a last independently of the side grippers to pull an upper over the last, and guiding means arranged to impart to said toe gripper in its movement heightwise of the last a movement also lengthwise of the last, said guiding means being adjustable to cause the toe gripper to move either forwardly or rearwardly lengthwise of the last.

50. 22. In a machine for shaping uppers over lasts, a toe gripper, side grippers, means for moving said toe gripper heightwise of a last independently of the side grippers to pull an upper over the last, and a swinging link connected to said toe gripper for guiding it and for imparting to it in its movement heightwise of the last a movement also lengthwise of the last, said link being adjustable to different positions to cause the toe gripper to move either forwardly or rearwardly lengthwise of the last.

55. 23. In a machine for shaping uppers over lasts, a toe gripper, side grippers, a spring arranged to operate said toe gripper to pull an upper over a last and of sufficient strength to subject the upper to substantially the full longitudinal tension required for the upper-shaping operation, means for rendering said spring effective to impart the upper-pulling movement to the toe gripper before the side grippers pull the upper, and means to enable the operator to return the toe gripper to its starting position against the resistance of said spring prior to the pulling of the upper by the side grippers.

60. 24. In a machine for shaping uppers over lasts, a toe gripper, side grippers, a spring for operating said toe gripper to pull an upper over a last, means for releasing the toe gripper to the action of said spring to cause it to pull the upper, power-driven means including a clutch arranged to be actuated thereafter to cause the side grippers alone to pull the upper, and means to enable the operator to return the toe gripper to its starting position against the resistance of said spring prior to the actuation of said clutch.

65. 25. In a machine for shaping uppers over lasts, a toe gripper, side grippers, a spring for operating said toe gripper to pull an upper over a last, a latch arranged to hold the toe gripper initially in its starting position and movable to release it to the action of said spring to cause it to pull the upper, power-driven means including a clutch arranged to be actuated thereafter to cause the side grippers alone to pull the upper, and means to enable the operator to move the toe gripper reversely into position to be held by said latch prior to the actuation of said clutch.

70. 26. In a machine for shaping uppers over lasts, a toe gripper, side grippers, a spring for operating said toe gripper to pull an upper over a last, means for releasing the toe gripper to the action of said spring to cause it to pull the upper, power-driven means including a clutch for thereafter operating the side grippers alone to pull the upper, and means to enable the operator to vary the force of the pull of the toe gripper on the upper while the upper is held under tension by the side grippers.

75. 27. In a machine for shaping uppers over lasts, a toe gripper, side grippers, a spring arranged to operate said toe gripper to pull an upper over a last independently of the side grippers and of sufficient strength to subject the upper to sub-

stantially the full longitudinal tension required for the upper-shaping operation, means for releasing the toe gripper to the action of said spring to cause it to pull the upper, and means to enable the operator to move the toe gripper in a direction to alter the force of its pull on the upper after it has been operated by said spring.

28. In a machine for shaping uppers over lasts, a toe gripper, side grippers, a lever movable to operate said toe gripper to pull an upper over

a last, a spring for operating said lever to impart to the toe gripper its upper-pulling movement independently of the side grippers, means for releasing said lever to the action of the spring, and another lever connected to said toe gripper lever and movable by the operator to alter the force of the pull applied to the upper by the toe gripper.
